Patented June 6, 1922.

FIG. 2.

Fig. 1.

Inventor:
Charles P. Mc Bee
by Dodson & Ron Atlys.

UNITED STATES PATENT OFFICE.

CHARLES F. McBEE, OF ATHENS, OHIO.

INDEX BOOK FOR FILING SYSTEMS.

1,418,315.

Specification of Letters Patent. Patented June 6, 1922.

Application filed September 17, 1921. Serial No. 501,382.

To all whom it may concern:

Be it known that I, CHARLES F. McBEE, a citizen of the United States, residing at Athens, in the county of Athens and State 5 of Ohio, have invented a new and useful Index Book for Filing Systems, of which the following is a specification.

My invention relates to filing systems and has for its object to provide a competent, 10 efficient and truly accurate index book which, without the necessity of close calculation or study, will enable a person to place proper reference characters on a communication so that it may be quickly filed in its proper 15 place, and may be instantly located at any desired time.

For convenience and brevity I have illustrated, and shall describe, my invention in its adaptation to the filing systems of the 20 transportation lines of the country.

In the conduct of general affairs of transportation lines, railway, steamship, aerial, and others, a great multiplicity of offices are maintained and each office must have its 25 own, independent, filing system. It will be understood that any one of these offices may have correspondence with other offices on its road, its own head office, or with offices or officers of other roads, or even with private 30 personages or business interests, and the great volume of this correspondence covers such a varied and multiplicity of subjects that no adequate system of general filing has heretofore been devised.

35 The lack of such a system has caused much confusion among the various offices and has otherwise caused much delay and oftentimes irreparable damage. This has been, unfortunately, forcibly demonstrated during the 40 period the railway systems of this country were consolidated, and it is to the solving of this problem that my invention is directed.

My invention resides in the taking of all 45 of the varied transportation means and grouping them together, preferably in alphabetical arrangement, each road having a designating numeral by which (through my system) it becomes identified and known throughout the allied transportation systems. In like manner I have, with great 50 care and thought, prepared a list of all subjects concerning which the various offices might have correspondence, or which might in any manner affect them, and each of these

subjects is identified by a character, preferably a numeral.

A full and complete understanding of my invention will be more readily obtained by reference to the following description and claims, taken in connection with the accompanying drawings, in which Figure I is a plan view of an open book showing the sheets on which the names of some railways are tabulated and showing also their respective identifying numerals; and

65 Figure II shows a similar view, the book being open to expose some of the subject listings with their identifying numerals.

Referring to the accompanying drawings the reference numeral 10 is used to indicate 70 a book, the body portion of which is made up of two groups of leaves, the group 11 containing the names of all the transportation lines, preferably arranged alphabetically, each provided with its identifying numeral 75 12, and the group 13 containing an alphabetical listing of all subjects, each with its identifying numeral 14.

It will be noted the names of the roads are 80 alphabetically arranged and their respective identifying numerals precede them, and likewise the list of subjects are alphabetically arranged and their respective identifying numerals precede them. This is the preferable arrangement though other arrangements are contemplated in my invention. 85 The pages of the two groups of leaves are preferably defined by projecting tabs with proper reference characteristics.

My invention, comprised by the book 90 made up as herein described, contains as hereinbefore set forth, a listing of all transportation lines, and all possible subjects on which they would have correspondence, and is designed to be placed in every office so that 95 its use and effectiveness will be complete and universal in character. However, it is not at all necessary to its utility that all roads adopt it, for it will be just as effective to the road adopting it as though all roads had 100 done so.

In its practical operation we will assume a bureau of the Baltimore and Ohio Railway is writing to the Pennsylvania Railway relative to absorption of terminal switching 105 charges. 38 is known by the writer to be the number of his own road; 945 is found to be the number of the subject and 24 is found

to be the number of the road he is writing to. These file numbers are placed upon the letter and appear as follows:

(38) 945-24.

5 This communication, bearing the identifying numerals as stated, is filed in the forwarding office under 945-24, and in the receiving office under 945-38. In replying, 10 the arrangement of the numerals appearing on the letter would be reversed and read—(24) 945-38.

15 While it is most desirable the writer should always give his number, it does not affect the proper filing if he should fail to do so, as the number can be located at once by 20 reference to the book, by the party receiving the letter.

In many offices certain bureaus are established and when such is the case, the writer 25 used his own bureau character as an addition to the above. For instance, we will assume it is Bureau H that is writing the letter. These file numbers are then placed on the letter and appear as follows:

(38) 945H-24.

It will be understood that my book in order to be complete in itself, has incorporated within it, all of the transportation lines 30 which are in, or touch the borders of the country, and an identifying character is arbitrarily assigned to it. Also all possible 35 subjects on which correspondence may take place, are classified and incorporated in the book and identifying characters are arbitrarily assigned to them. However, it is my purpose to provide for adding additional lines or subjects at any time, and these will 40 be furnished as supplements.

It is instantly apparent the adoption of my book by any one office, and filing in accordance therewith, will cause every letter 45 going out of, or being received in that office, to be filed not only as to the road but as to the subject matter of the letter, and my book is an effective key for accomplishing this and for locating any letter instantly when it is called for. Practical demonstrations of its use have already been made by 50 leading railways of the country, which have adopted it, and has proven that any letter

called for can be instantly located by a file clerk. It has also proven exceedingly effective as a labor-saver, for one file-clerk can 55 do the work which heretofore required the services of a large number.

One great object accomplished by my invention is to standardize and unify the work between transportation lines, for interchange of correspondence, relative to numerous subjects, is essential, and heretofore much confusion through inadequacy of filing has occurred and many times letters are 60 completely lost and great damage has resulted. My invention, already adopted by 65 many of them, has clarified that condition and is forcefully proving its utility.

For convenience, I have described my invention as it is used in the office of transportation lines, but it can be applied with equal force and utility to any other branches of industry, and I do not wish to be understood as limiting the invention to any particular class.

Having thus described my invention, what I claim and desire to secure by Letters Patent of the United States is:

1. An index book for filing systems comprising a group of leaves containing a classified list of allied industries, and an identifying character for each of same, and a classified list of subjects, pertaining to possible correspondence matters, and an identifying character for each subject.

2. An index book for filing systems comprising a group of leaves containing an alphabetically arranged list of allied industries and a reference character for each of the same, and a second group of leaves containing an alphabetically arranged list of subjects pertaining to said industries with a reference character for each subject.

3. An index book for filing systems comprising a list of industries arranged for convenient reference and an identifying character for each industry, with a list of subjects applying to the industries, arranged for convenient reference and an identifying character for each subject.

CHARLES F. McBEE.
